UNITED STATES PATENT OFFICE.

THOMAS WHEATLEY, OF SYRACUSE, NEW YORK.

AIR-VALVE.

SPECIFICATION forming part of Letters Patent No. 664,699, dated December 25, 1900.

Application filed April 21, 1899. Serial No. 713,868. (No model.)

To all whom it may concern:

Be it known that I, THOMAS WHEATLEY, of Syracuse, in the county of Onondaga, in the State of New York, have invented new and useful Improvements in Air-Valves, of which the following, taken in connection with the accompanying drawings, is a full, clear, and exact description.

My invention relates to automatic air-valves for radiators and other steam-chambers; and it consists in a particular form of valve adapted to close the opening in any position of the valve and in certain details of construction relating to the alinement of the expansion rod and float, the drawing off of the water of condensation, &c.

My invention will be better understood by reference to the accompanying drawings, in which the same numerals of reference indicate the same parts in all the figures.

Figure I is a vertical section of my improved air-valve. Fig. II is a corresponding section without the float, showing the valve closed. Fig. III is an enlarged section of the upper end of the preceding, indicating the variation in the position of the valve. Fig. IV is a side elevation of the valve and float. Fig. V is a top plan view of the base.

In the figures, 1 indicates the base, having a screw-threaded tip 2 for attachment to the radiator, provided with inlet 3, communicating with the interior of the base at its lowest point, so that the water of condensation will flow back easily into the radiator and not accumulate in the interior of the air-valve.

4 is an integral circular guide-wall in the center of the base, in which fits the lower end of the expansion-rod, 5 being a perforation formed at the bottom of said wall adjacent to the inlet, and also for the return of the water of condensation.

6 is the inclined outer surface of the base, and 7 an interior screw-thread in its upper edge for the attachment of the shell 8, having at its upper end the internally-screw-threaded neck 10 and enlarged under tip 11, adapted to receive the packing, 12 being the screw or tube fitted to said tip and screw-threaded to engage with the neck formed with outlet 13 and preferably with an inverted-cup-shaped valve-seat 14, 15 being a slot in its upper end for the screw-driver, and 16 the packing.

17 is the cap, screw-threaded to engage with the tip, and 18 a central perforation therein registering with the outlet.

55

19 is the expansion-rod, formed with a small lower tip 20 and perforation 21 for guide-rod 22 on the interior of the float 23. The float is formed with groove 24 for the passage of the air and has secured to its upper end the valve 25, having its tip 26 semispherically formed to fit the valve-seat snugly in any position which the parts may assume and close the opening tight. While this may seem a slight variation in form, yet it is a great practical improvement, fitting the valve-seat of any form and closing the outlet in any position. All valves of this kind have heretofore been provided with pointed or conical tips, which failed to close the outlet unless in perfect alinement and often scratched the metal, causing a permanent leak. It is evident that this semispherically-tipped valve may be used in various constructions, but is particularly important in connection with a float, which is liable to slip to one side and tip. In my detail construction of float-valve perfect alinement is preserved when the parts are in normal position, and even when the tube 12 is removed the slipping of the float 80 on the rod is prevented and all possibility of their tipping over away from the opening, making the readjustment of the parts difficult.

75

It will be noted that the lower stem or guide-rod of the valve is seated loosely in the socket in the expansible rod, which allows the valve a slight lateral movement relative to said rod, permitting the valve to be guided to its seat to close the outlet, and when the float is employed to be guided independent of the expansible rod.

85

Having described my invention, what I claim as new, and desire to secure by Letters Patent, is—

95

1. In an air-valve, the combination of a valve-seat, approximately cup shape, a semi-spherical valve coöperating therewith, and an expansible rod adapted to close the valve, said valve having a slight lateral movement relative to the expansible rod.

100

2. In an air-valve the combination of a valve-seat, approximately cup shape, a semi-spherical valve coöperating therewith, an ex-

5. expansible rod adapted to close the valve, said valve having a slight lateral movement relative to the expansible rod, and a float rigidly secured to the valve and adapted to move the same independent of said expansible rod.

6. In an air-valve, the combination of an inverted-cup-shaped valve-seat, a semispherical valve coöperating therewith, and an expansible rod adapted to close the valve, said valve being loosely and removably seated in the expansible rod and having a slight lateral movement relative thereto.

7. In an air-valve, the combination of an inverted-cup-shaped valve-seat, a semispherical valve coöperating therewith, an expansible rod adapted to close the valve, said valve being loosely and removably seated in the expansible rod and having a slight lateral movement relative thereto, and a float rigidly secured to the valve and adapted to move the same independent of said expansible rod.

8. In an air-valve, the combination of an inverted-cup-shaped valve-seat, a semispherical valve coöperating therewith, and an expansible rod having its lower end guided against

lateral movement, said valve being loosely seated in and guided by the expansible rod.

9. In an air-valve, the combination of an inverted-cup-shaped valve-seat, a semispherical valve coöperating therewith, an expansible rod having its lower end guided against lateral movement, said valve being loosely seated in and guided by the expansible rod, and a float rigidly secured to the valve and adapted to move the same independent of said expansible rod.

10. In an air-valve, the combination of a valve-seat, a valve coöperating therewith, an expansible rod having its lower end guided against lateral movement, said valve being loosely seated in and guided by the expansible rod, and a float rigidly secured to the valve and adapted to move the same independent of said expansible rod.

11. In testimony whereof I have hereunto signed my name.

THOMAS WHEATLEY. [L. S.]
